UNITED STATES PATENT OFFICE.

LORENZO GRISERI, OF NEW YORK, N. Y.

AUTOMATIC PIANO.

No. 919,002.

Specification of Letters Patent.

Patented April 20, 1909.

Application filed April 9, 1906. Serial No. 310,774.

To all whom it may concern:

Be it known that I, LORENZO GRISERI, a subject of the King of Italy, residing at New York, in the county and State of New 5 York, have invented a new and useful Improvement in Automatic Pianos, of which the following is a specification.

This invention relates to the class of automatic pianos having means for rapidly 10 vibrating the hammers, to produce an effect similar to that of the mandolin.

Its object is the provision of an efficient action of this character which is inexpensive in construction.

15 In the accompanying drawing: Figures 1 and 2 are fragmentary cross sections of a mechanical piano embodying the invention, showing different positions of the hammer and coöperating parts. Fig. 3 is a fragmentary sectional elevation of the instrument showing the means of driving the hammer vibrating cylinder.

Similar letters of reference indicate corresponding parts throughout the several 25 views.

A indicates a pin barrel arranged horizontally in the case B, and C indicates one of the keys which coöperates therewith. In the construction shown, these keys are arranged 30 on the rear side of the pin barrel and pivoted between their ends to the customary bar D which extends lengthwise of the barrel. Each key is provided with a spring e which tends to swing its lower arm toward the barrel and which is compressed 35 when the key is tripped by a pin of the barrel.

f indicates one of the hammers of the mandolin action arranged above the keys C 40 and carried by an upright lever F pivoted near its lower end upon a longitudinal rod g. This rod is mounted in a supporting bar H extending lengthwise of the pin barrel and is preferably of sufficient length to form 45 a common pivot for all of the hammer-levers.

I is an actuating or vibrating device for 50 swinging the several hammer levers in one direction, preferably away from the strings.

55 The device shown in the drawings consists of a rotary horizontal drum or cylinder arranged below said levers and having annular rows of trip-pins or projections i, one row for each lever. These pins are adapted to trip over a wear plate or tongue j secured to the lower end of the hammer-lever on the

front side of its pivot. The hammer-lever is swung against the corresponding string by a spring k attached at its front end to the lower end of the lever in front of its pivot and at its rear end to a vertically swinging controlling lever L fulcrumed between its ends, preferably on the same pivot-rod g as the hammer-levers. The lever L has a longitudinal slot l in which the lower 60 end of the hammer-lever plays, and the front end of this slot is so arranged that when the forward arm of said lever is raised, the front end of the slot bears against the adjacent edge of the hammer-lever and 65 causes it to swing upward with the controlling lever, thereby withdrawing the tongue of the hammer-lever from the path of the pins i. The controlling lever is normally held in the last-named position by a 70 spring m secured at its lower end to the supporting bar H and at its upper end to an arm or extension n depending from the rear end of the controlling-lever. The spring m is preferably arranged in an oblique opening m¹ of the bar H to enable the 75 spring to be made comparatively long.

The lower end of the extension n is arranged against or adjacent to the front side of the corresponding key C, so that when the 80 latter is swung forwardly by a pin of the rotary barrel A it moves the extension in the same direction, thereby depressing the front arm of the controlling lever and bringing the tongue of the hammer-lever into the path 85 of the pins of the cylinder I. As long as the parts occupy this position, which is shown in Fig. 2, the hammer is rapidly vibrated by the alternate action of the pins i and the spring k, in an obvious manner, causing the 90 hammer to strike the string numerous times for every note and producing a mandolin effect. As soon as the tripped key clears the pin of the rotary barrel, its spring swings it away from the extension n allowing the 95 spring m to elevate the controlling lever and lifting the hammer-lever out of the engagement with the actuating cylinder I, as shown in Fig. 1.

As shown in the drawings, the extension n 100 is preferably provided with a horizontal adjusting screw n¹ having a head or button against which the key C bears.

The hammer-actuating cylinder I may be driven by any suitable means. In the construction illustrated in the drawings, the cylinder-shaft is driven from a shaft o ar-

ranged at right angles thereto, by a belt σ^1 running around pulleys σ^2 σ^3 , the shaft σ also driving the pin barrel A through the usual worm gearing p p^1 .

I claim as my invention:

1. In a musical instrument of the character described, the combination of a vibrating device, a hammer-lever arranged above said device and adapted to be moved in one direction by the same, a spring for moving the hammer-lever in the opposite direction, a vertically-swinging controlling lever arranged adjacent to the hammer-lever and provided on the front side of its pivot with a downward extension and on the rear side thereof with a portion adapted to bear against the rear side of the hammer-lever, a spring for normally raising the rear arm of the controlling lever, and means acting on said extension for depressing the rear end of the controlling lever, substantially as set forth.
2. In a musical instrument of the character described, the combination of a vibrating device, a hammer-lever arranged above said device and adapted to be moved in one direction by the same, a spring for moving the hammer-lever in the opposite direction, a vertically-swinging controlling lever arranged adjacent to the hammer-lever and provided on the front side of its pivot with a downward extension and on the rear side

thereof with a portion adapted to bear against the rear side of the hammer-lever, a spring for normally raising the rear arm of the controlling lever, a pin barrel, and a key actuated by the pin barrel and acting upon said extension to depress the rear arm of the controlling lever, substantially as set forth.

3. In a musical instrument of the character described, the combination of a support, a vertically-swinging, bent controlling lever pivoted thereto and having a longitudinal slot in its horizontal portion, a hammer-lever having its lower end pivoted in said slot, the rear end of the slot being arranged to bear against the hammer-lever in the elevated position of the slotted end of the controlling lever, a spring connecting the hammer-lever with the controlling lever and tending to swing the hammer-lever rearwardly, a vibrating device having projections adapted to swing the hammer-lever forwardly, a spring for normally elevating the slotted end of the controlling lever, and means for depressing said end of the controlling lever, substantially as set forth.

Witness my hand this 19 day of March, 1906.

LORENZO GRISERI.
